[57] CLAIM

The ornamental design for a captain's sleigh bed, as shown and described.

DESCRIPTION

FIG. 1 is a elevational perspective view of a captain's sleigh bed showing my new design;

FIG. 2 is a top view of the sleigh bed;

FIG. 3 is a right side view of the sleigh bed, the left side view being a mirror image in appearance;

FIG. 4 is a right end view of the sleigh bed; and,

FIG. 5 is a left end view of the sleigh bed.

The bottom of the article is not part of the claimed design. The inside of the footboard not shown is the same as the inside of the headboard shown in FIG. 1.
